United States Patent Office

Des. 215,852
Patented Nov. 4, 1969

215,852

LASER OR SIMILAR ARTICLE

Oskar Heininger, Framingham Center, Mass., assignor
to Sylvania Electric Products Inc, a corporation of
Delaware

Filed Oct. 15, 1968, Ser. No. 14,103

Term of patent 14 years

Int. Cl. D14—04

U.S. Cl. D26—14

FIG-2

FIG-4

FIG-3

FIG-5

FIG-6

FIGURE 1 is a perspective view of a laser or similar article showing my new design;

FIGURE 2 is a side elevation thereof;

FIGURE 3 is a front elevation thereof viewed on line 3—3 of FIGURE 2;

FIGURE 4 is a top plan view thereof;

FIGURE 5 is a side elevation thereof viewed on line 5—5 of FIGURE 4; and,

FIGURE 6 is a rear elevation thereof viewed on line 6—6 of FIGURE 2.

The dominant features of my design reside in the portions shown in full lines.

I claim:
The design for a laser or similar article, as shown and described.
